CRYSTAL DIODE UNIT

Howard M. Wadsworth, Liverpool, N. Y.
Application April 3, 1952, Serial No. 280,410

5 Claims. (Cl. 317—236)

The present invention relates to a crystal diode capsule and more particularly to structure for supporting the electrode of a crystal assembly in a sealing envelope or casing.

In crystal diode assemblies such as germanium crystal units as now commercially available, a tiny plate of crystal is rigidly mounted on the end of a wire electrode, and a "cat whisker" of very fine wire is mounted on the end of a similar electrode, and the electrodes are rigidly mounted and hermetically sealed in a tubular sheath or casing of dielectric material such as a plastic tube, in such position that the end of the cat whisker rests on the surface of the crystal with a predetermined light pressure.

It is customary to make the sealing connection between the electrodes and the plastic tube by means of metal thimbles or ferrules which are cemented in the ends of the tube and are soldered to the electrodes. During the assembly of the parts it is desirable that the thimbles hold the electrodes frictionally with sufficient security to maintain their adjustment prior to and during the final sealing operation.

When it is considered that the external diameter of the electrodes is only about .079 inch, and their longitudinal adjustment must be held to within about .001 inch to maintain the pressure of the cat whisker on the crystal within accepted tolerances, it is apparent that the provision of thimbles having the requisite elasticity, stiffness and grip on the electrodes, and security of attachment to the tubing so as not to be loosened when the electrodes are inserted, presents a very difficult problem. Various forms of slotted or crimped thimbles have been tried, but none of them have been entirely satisfactory, due to difficulty in maintaining spacing and alignment of the electrodes, breakage, leakage etc.

It is an object of the present invention to provide a novel crystal assembly unit of which the parts are economical to produce and may be easily assembled and sealed without loss of adjustment.

It is another object to provide such a device incorporating mounting thimbles for the electrodes which provide a plurality of axially extending line bearings spaced about the peripheries of the electrodes and gripping them with substantially uniform pressure throughout the major portion of the length of the tubular casing.

It is another object to provide such a device in which the thimbles are free from slots or sharp bends which would be conducive to localized stresses and would render it difficult to obtain a tightly sealed connection.

Another object is to provide such a device in which the tubular casing is of vitreous material, and the thimbles are sealed in the ends of the tube by a fusing operation prior to the assembly of the electrodes.

Further objects and advantages will be apparent from the following description taken in connection with the accompanying drawing in which:

Fig. 1 is a substantially mid-sectional view of a crystal unit constituting a preferred embodiment of the invention

2

on a highly enlarged scale, the electrodes being shown in elevation;

Fig. 2 is an end view of the unit shown in Fig. 1;

Fig. 3 is still further enlarged end view of a thimble;

5 Fig. 4 is a view similar to Fig. 3 of the opposite end of the thimble; and

Fig. 5 is a longitudinal section through a thimble.

In Fig. 1 of the drawing there is illustrated a cylindrical electrode 1 on which a plate 2 of crystalline material such as germanium is fixedly mounted in any suitable manner. A second electrode 3 has a fine wire cat whisker 4 attached at one end thereto as by welding, the free pointed end of the cat whisker being arranged to contact the surface of the crystal 2.

15 A hollow tubular casing or envelope 5 of suitable material such as glass loosely surrounds the electrodes 1 and 3 and a pair of thimbles or nipples 6 and 7 are mounted in the ends of the casing 5 and support and seal the electrodes in the casing. Each thimble is provided on 20 its outer end with a radial flange 8 which is rigidly mounted and sealed in the end of the casing 5, preferably by fusing the glass around the flange as shown at 9.

According to the present invention, these nipples are so formed as to grip the electrodes elastically throughout a 25 considerable portion of their length by means of straight line bearings which hold the electrodes in proper alignment and offer sufficient resistance to endwise movement of the electrodes to prevent their shifting accidentally before or during the final sealing operation. For this purpose, the skirts 11 of the thimbles which are originally cylindrical are distorted for a portion of their length as shown at 12 in Figs. 4 and 5 by displacing longitudinal strips or panels of the skirt inwardly. As here illustrated three such panels or lands 12 are formed so that 30 the section of the skirt as deformed is roughly triangular in shape and substantially uniform for a major portion of its length as illustrated in Figs. 1 and 5, the panels or lands being connected by smoothly curved outwardly projecting portions 13 as shown in Fig. 4, whereby the panels 35 can flex radially altho the skirt is continuous and free from slits or openings.

It will be understood that more than three strips or panels may be formed if desired, and the strips may be curved inwardly instead of being flat as illustrated.

40 45 The strips 12 extend inwardly to such an extent that a circle inscribed in a right section of the skirt is of slightly smaller diameter than the diameter of the electrodes. When an electrode is pressed into the nipple therefore it has a plurality of line contacts with the skirt which grip the electrode firmly due to the elasticity of the curved portions 13 of the skirt.

In assembling the device, the two thimbles 6 and 7 are first fused into the tube 5 while maintained in alignment on a suitable mandrel. The mandrel is then withdrawn, 50 and the electrodes inserted by pressing them through the nipples until the cat whisker 4 engages the crystal 2 with the desired amount of pressure. The units can then be handled without danger of losing the adjustment of the cat whisker, by virtue of the strong gripping engagement of the panels 12 of the skirts of the nipples.

55 The capsule is then finally sealed by soldering the throats of the nipples to the electrodes as shown at 14 in Fig. 1.

Although but one embodiment of the invention has 60 been shown and described in detail it will be understood that changes may be made in the precise form and dimensions of the parts without departing from the spirit of the invention.

What is claimed is:

70 1. In a crystal diode assembly, a cylindrical electrode, a crystal plate fixed on one end thereof, a second electrode, a spring wire filament attached at one end there-

to, a hollow cylindrical casing of dielectric material, and a pair of tubular thimbles of elastic metallic material extending into the ends of the casing, said thimbles having radial terminal flanges sealed to the ends of the casing, the bodies of the thimbles being formed with a plurality of axially extending lands between which the electrodes are firmly gripped, said land portions of the thimbles being equidistantly spaced about the bodies of the thimbles, and the portions of said bodies between the lands being smoothly curved and adapted to bear frictionally throughout their length on the interior of the cylindrical casing.

2. In an electrical coupling unit, a hollow cylindrical casing, a pair of hollow thimbles having radial flanges rigidly mounted in the ends of the casing and tubular skirts which are continuous throughout their length extending into the casing, a cylindrical electrode extending into each end of the casing through said thimbles, each of said skirts being distorted inwardly for a portion of its length at a plurality of circumferentially spaced areas to form axially extending flattened panels, said electrodes being frictionally held and maintained in alignment by line contact with said inwardly displaced areas of the skirt.

15
20

3. A crystal diode assembly as set forth in claim 1 in which the gripping portions of the thimbles extend for a major portion of the length of the thimbles, with substantially uniform cross-section.

5 4. A crystal diode assembly as set forth in claim 1 in which the casing is formed of vitreous material, and the flanges of the elastic metallic thimbles are fused in the ends of the casing.

10 5. A unit as set forth in claim 2 in which the skirts of the thimbles engaging the electrodes are of substantially uniform cross-section for a major portion of their length, said panels being joined by smoothly curved outwardly projecting portions permitting radial flexure of the panels.
